JOHN R. DALLERUP, OF HOUSTON, TEXAS, ASSIGNOR TO REED ROLLER BIT COMPANY,
OF HOUSTON, TEXAS, A CORPORATION OF TEXAS

DRILL CUTTER MOUNTING

Application filed January 19, 1929. Serial No. 333,691.

This invention relates to drills, and more particularly to drill cutter mountings.

The invention has for one of its specific objects the provision of an adjustable cutter mounting whereby a cutter may be mounted in various positions in a drill head to successively perform the functions of cutters of different sizes.

Other objects and uses will hereinafter appear.

Referring to the accompanying drawings, Fig. 1 is a fragmentary sectional side elevation of a mounting for cross roller cutters; Fig. 2, a detailed end view taken at right angles to Fig. 1; Fig. 3, a fragmentary side elevation illustrating a mounting for reamer cutters; and Fig. 4, a horizontal section on the line 4-4 of Fig. 1.

The bit head 1, illustrated by Figs. 1 and 2, is of the type having a pair of oppositely depending extensions 1a with a recess 1b therebetween, into which water or slush is discharged from the central course 1c. Extensions 1a form bearings for the cross roller cutter pin 2.

If the lowermost portions 1a' of extensions 1a are not of sufficient thickness, that is, if there is insufficient material below the bore in which the pin 2 is secured, the portions 1a' are worn away in the use of the bit, and pin 2, with cross roller cutters 3 thereon, will drop out of the head. In order that the portions 1a' may be of sufficient thickness and at the same time to eliminate the necessity of changing the usual size or position of the cutters, the invention provides the pin 2 of non-circular cross section and co-operating gibs a, b, and c. As shown, the pin 2 is of a square cross section and the gibs a, b, and c of rectangular cross sections, but it is to be understood that the forms thereof may be changed.

Cross roller cutters 3 are mounted upon cylindrical bushing 5, which has a bore adapted to non-rotatably receive the pin and gibs. A bridge 6, of the usual type, may be used as a support. This bridge is preferably made of a plate having an opening through which bushing 5 extends, and having an upper end shaped to rest against the upper

wall of recess 1b. Pin 2 may be secured in place by means of a set screw 7, or otherwise.

The gibs a, b, and c are of different thicknesses, as shown in the drawings, and the gibs and the pin are separable. It will be obvious that when the gibs a, b, and c are on the uppermost side of the pin 2, the cutters 3 will be in their uppermost position in the head; and when the gibs a, b, and c are on the lowermost side of the pin 2 the cutters will be in their lowermost position in the head; and intermediate positions of the cutters may be effected by placing one or more of the gibs a on one side of the pin and the remaining gib or gibs on the other.

Referring now to Figs. 3 and 4. To increase the diameter of a well bore, it is now the custom to remove the original reaming cutters from the head and to mount larger cutters in the place thereof, the bit heads now in use being so constructed that cutters of various sizes may be mounted therein. And at times it is necessary to remove the original cutters and to mount smaller cutters in the place thereof, to permit the passage of the bit through a pipe casing of a comparatively small internal diameter. It is, therefore, necessary for the driller to have on hand reaming cutters of various sizes. The application of this invention to reamers is illustrated by Figs. 3 and 4, wherein the reamer body 12 has a rounded recess 12a in which the reamer cutters 13 are mounted. A pin 14 of non-circular cross section and gibs d, e and f non-rotatably support cylindrical bushing 16 upon which reamer cutters 13 revolve. The pin 14 may be held in place by a suitable retaining set screw 17.

It may be advantageous for various reasons, of which the ability to pass through a pipe casing of a comparatively small diameter has hereinabove been mentioned, to mount the reamers in their innermost position. To do this it is necessary only to place the gibs d, e and f on the innermost side of the pin 14. Should it become necessary to cut a bore of a relatively great diameter, the gibs d, e and f may be moved to the outermost side of the pin 14. Thus, the position of the

reamer cutters 13 may be so varied that they will perform the function of a smaller or a larger reamer.

Should it become desirable to mount the 5 reamer in any intermediate position, one or more of the gibbs may be moved from one side of the pin to the other.

If desired, a supporting bridge 18 may be used as shown in Fig. 3.

10 While I have illustrated and described the use of three gibbs of different thicknesses, it is to be understood that any number of gibbs of any form may be used to effect different adjustments. And so my invention is not 15 limited to the preferred embodiment illustrated and described.

I claim:

1. In a drill, a head, a pin non-rotatably supported by said head, a plurality of gibbs, a 20 bushing upon said pin and gibbs, and a cutter supported by said bushing, said gibbs being capable of occupying a plurality of positions in said bushing relative to said pin to vary the position of said cutter with respect to 25 said head.

2. In a drill, a head, a pin non-rotatably supported by said head, said pin being non-circular in cross section, a plurality of gibbs, a bushing on said pin and gibbs, and a cutter 30 on said bushing, said gibbs being capable of occupying a plurality of positions in said bushing relative to said pin to vary the position of said cutter with respect to said head.

3. In a drill, a head, a pin non-rotatably supported by said head, a plurality of gibbs, a bushing having a bore shaped to non-rotatably receive said pin and gibbs, and a roller cutter on said bushing, said gibbs being capable of occupying a plurality of positions in 40 said bore relative to said pin to vary the position of said cutter with respect to said head.

4. In a drill, a head, a pin non-rotatably supported by said head, a plurality of gibbs of different sizes, a bushing upon said pin and 45 gibbs, and a cutter supported by said bushing, said gibbs being capable of occupying a plurality of positions in said bushing relative to said pin to vary the position of said cutter with respect to said head.

5. In a drill, a head, a pin non-rotatably supported by said head, said pin being non-circular in cross section, a plurality of gibbs of different sizes, a bushing on said pin and gibbs, and a cutter on said bushing, said gibbs 55 being capable of occupying a plurality of positions in said bushing relative to said pin to vary the position of said cutter with respect to said head.

6. In a drill, a head, a pin non-rotatably supported by said head, a plurality of gibbs of different sizes, a bushing having a bore shaped to non-rotatably receive said pin and gibbs, and a roller cutter on said bushing, said gibbs being capable of occupying a plurality 65 of positions in said bore relative to said pin

to vary the position of said cutter with respect to said head.

7. In a drill, a head, a pin non-rotatably supported by said head, a plurality of gibbs, and a cutter on and supported by said pin and gibbs, said gibbs being capable of occupying a plurality of positions in said cutter relative to said pin to vary the position of said cutter with respect to said head.

8. In a drill, a head, a pin non-rotatably supported by said head, said pin being non-circular in cross-section, a plurality of gibbs, and a cutter on and supported by said pin and gibbs, said gibbs being capable of occupying a plurality of positions in said cutter relative to said pin to vary the position of said cutter with respect to said head.

9. In a drill, a head, a pin non-rotatably supported by said head, a plurality of gibbs of different sizes, and a cutter on and supported by said pin and gibbs, said gibbs being capable of occupying a plurality of positions in said cutter relative to said pin to vary the position of said cutter with respect to said head.

10. In a drill, a head, a pin non-rotatably supported by said head, said pin being non-circular in cross section, a plurality of gibbs of different sizes, and a cutter on and supported by said pin and gibbs, said gibbs being capable of occupying a plurality of positions in said cutter relative to said pin to vary the position of said cutter with respect to said head.

In testimony whereof, I hereunto affix my 100 signature.

JOHN R. DALLERUP.
